Attorney

UNITED STATES PATENT OFFICE

VICTOR MEYER, OF BROOKLYN, NEW YORK

BRIDLE BIT

Application filed May 6, 1930. Serial No. 450,190.

The present invention relates to improvements in bridle bits, and more particularly it pertains to bits of the so called two part mouthpiece type.

5 It is an object of the invention so to construct a bridle bit which will prevent squeezing of an animal's cheeks against the teeth of the animal.

10 Other objects of the invention will appear as the nature of the invention is understood, and by reference to the accompanying specification and drawing, wherein,

15 Figure 1, is a view in front elevation and a bridle bit constructed in accordance with the present invention.

Figure 2, is a top plan view thereof, and

Figure 3, is a detail sectional view taken on the line 3—3 of Figure 2.

20 Referring specifically to the drawing, the bit comprises a mouthpiece A preferably formed by two members 5 and 6, which members are each provided with an eye or loop 7 which when interconnected as shown, form a two part mouthpiece in which the 25 two parts are connected together for relative movement. Bridle strap attaching rings 8 may be secured to the members 5 and 6 of the bit in any desired manner.

25 It will be noted from Figure 2, that each 30 of the members 5 and 6 is slightly curved longitudinally, and that each is provided near its free end with a substantially circular portion 9, and by reference to this same figure, it will be noted that each of 35 the members 5 and 6 is provided with a relatively enlarged portion 10 near the eye thereof. This construction provides a relatively large tongue engaging surface at the center or connected portions of the members 40 5 and 6, and this portion will serve to prevent the bit from squeezing a horse's mouth and tongue and also to place the smallest surface on the heaviest bearing point and to prevent the bit from doubling up. This result is obtained by reason of the fact that 45 the members 5 and 6 are projected rearwardly in a horizontal plane to form the large portion 10.

50 From the foregoing, it will be apparent that the herein described construction pro-

vides a device in which the several objects of the invention are carried out in a simple, yet highly efficient manner.

What is claimed, and desired to secure by Letters Patent of the United States, is:

55 1. A bit comprising two loosely connected members, each of which members is formed with an enlarged portion at a point adjacent the point of connection with the other member, said enlarged portion extending only in a direction rearwardly of the bit.

60 2. A bit comprising two members loosely connected together, each of said members having an enlarged irregular portion adjacent its point of connection with the other member, said enlarged irregular portion presenting a flat face extending rearwardly of the bit.

65 In testimony whereof I affix my signature.
